CLIP FOR ATTACHING PAILS TO
SUPPORTING CHASSIS

Elmer H. Bard, Muskegon, Mich., assignor to
Geerpres Wringer, Inc., Muskegon, Mich., a
corporation of Michigan

Application June 18, 1949, Serial No. 99,940

1 Claim. (Cl. 280—179)

1

This invention relates to an improved clip and more particularly to a clip adapted for attaching a pail or tank to a supporting chassis.

In conventional caster mounted tanks, such for example, as those used in mopping outfits, it is customary to employ a spider having locating projections which register with a portion of a supporting flange on the tank and it is customary to secure the pail to the spider by drilling holes through the spider projections and tank flange and securely fastening the two together by bolts extending through the drilled holes and receiving cooperating nuts.

It is an object of the present invention to provide an improved clip which may be easily applied for attaching the tank to the spider without the necessity of drilling the above mentioned hole and without the use of the above mentioned bolts.

It is a further object of the invention to provide such a clip which is simple in design, which may be economically manufactured and which is reliable and efficient in operation.

Other and more detailed objects of the invention will become apparent from a consideration of the drawing, the following specification and the appended claim.

In the drawing:

Figure 1 is a perspective view of a caster mounted tank in which the tank is secured to its supporting chassis by clips embodying the present invention;

Fig. 2 is a broken greatly enlarged view of that portion of the construction illustrated in Fig. 1, indicated by the circle 2; and,

Fig. 3 is a perspective view of the clip illustrated in Figs. 1 and 2.

It will be appreciated from a complete understanding of the present invention that the improved clip thereof may be employed in a wide variety of uses. In an illustrative but not a limited sense, the improved clip of the present invention is herein illustrated and described as a means for attaching the tank or pail of a mopping outfit to its supporting chassis.

Referring to the drawing, the mopping outfit generally indicated at 10, and illustrated in Fig. 1, comprises a tank 12 which is supported on a chassis generally indicated at 14 and may carry a conventional wringer illustrated in broken lines at 16.

The tank 12 illustrated in the drawing is a conventional cylindrical metal tank having a transversely extending bottom wall 18. The cylindrical side wall 20 of the tank extends downwardly below the bottom 18 to define an

annular supporting flange 22, the lower end portion 24 of which is reversely turned outwardly and terminates in an upwardly facing externally disposed annular shoulder 26.

The chassis 14 comprises a spider 28 supported on casters 30 and engaging the lower surface of the supporting flange 22 at a plurality of angularly spaced points, to support the tank 12. At each of these points the spider 28 extends outwardly of the tank 12 and is provided with an aperture 32 extending vertically therethrough which receives an upwardly extending stud portion 34 carried by the caster 30 and the upper end of which is threaded to receive a nut 36 for securing the caster 30 to the spider 28.

In accordance with the above-mentioned conventional construction, the spider 28 illustrated in the drawing also includes an upwardly extending locating boss 38 spaced inwardly of each of the apertures 32 and adapted to be disposed adjacent the supporting flange 22 of the tank 12 and substantially in engagement with the inner surface thereof. It will be appreciated that this portion functions as a locating tab and is the portion to which the supporting flange was secured by screws in the above mentioned prior practice of attaching the tank to its supporting chassis.

To this point the described construction is conventional and the present invention relates to an improved clip for attaching the tank 12 to the supporting chassis 14. The clip 40 of the present invention is illustrated in perspective in Fig. 3 and comprises a generally flat and rectangular plate having an aperture 42 adapted to receive the stud portion 34 of the caster 30, and having the corners at its outer end deformed downwardly to define a pair of spaced legs 44. The inner end portion of the clip 40 is offset upwardly to define a finger portion 46 adapted to extend over and engage the upwardly facing shoulder 26. When the clip is mounted in place, as best illustrated in Fig. 2, the legs 44 project downwardly and engage the upper surface of the spider 28 and the finger portion 46 engages the shoulder 26. By these engagements, the clip 40 is supported in generally parallel and slightly spaced relation above the upper surface of the spider 28. It will now be appreciated that when the nut 36 is tightened down against the clip 40, the engagement of the finger portion 46 with the shoulder 26 on the tank 12 firmly clamps the tank 12 to the spider 28.

It will now be appreciated that the clips 40 may be readily used with a spider 28 of conventional construction and including the upwardly

extending projections 38 which function only as locating projections when the clips 40 are used, or that when the clips of the present invention are employed, these clips may perform the locating function and a spider 28 may be used which does not include the projections 38. Further, it will be appreciated that the clips of the present invention may be used with a tank the supporting flange or lower edge of which has an enlarged or bead portion, the upper surface of which may be engaged by the clip in the same manner as the above described engagement of the clip 40 with the shoulder 26.

While only one form of the invention has been illustrated and described in detail, it will be readily appreciated by those skilled in the art that numerous modifications and changes may be made without departing from the spirit of the invention.

What is claimed is:

In combination, a caster mounted tank having a downwardly extending supporting flange defining, adjacent its lower limit, an externally disposed upwardly facing shoulder, a spider supporting said tank at a plurality of spaced points about said supporting flange and having a plurality of vertically extending apertures therethrough individual to and disposed outwardly of said points, a plurality of casters individual to

10 said apertures supporting said spider and having stud portions extending upwardly through said apertures and receiving nuts on their upper ends, and a plurality of clips attaching said tank to 15 said spider, each of said clips comprising a plate overlying a portion of the upper surface of said spider and having a circular aperture receiving said stud portion therethrough, said plate having a pair of spaced legs at one end engaging said upper surface of said spider and an offset finger portion at the other end engaging said shoulder on said supporting flange of said tank so that upon tightening of said nut on said stud portion said tank will be firmly held against said spider, said stud portions of said casters and said nuts cooperating to mount said spider on said casters and to secure said clips in place to mount said tank on said spider.
